BABY JUMPER

Howard W. Anderson, Wall, S. Dak.

Application February 10, 1942, Serial No. 430,273

7 Claims. (Cl. 155—18)

This invention relates to baby jumpers, and its general object is to provide a device of that character which is not only capable of use as a jumper, but for other purposes, such as for example, a high chair and perambulator, as well as an auxiliary seat for use by a child, in a motor vehicle.

A further object is to provide a device in the form of a baby jumper, that can be readily converted into a high chair and includes a detachable footrest and food tray for that purpose and the device also includes ground engaging wheels and handled means, to bring about the function thereof as a perambulator.

Another object is to provide a baby jumper that includes a removable seat and an attachment for the seat, so that the latter can be applied to the back rest of a seat of an automobile.

A still further object is to provide a device of the character set forth, that is simple in construction, inexpensive to manufacture, and extremely efficient in operation, use and service.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a perspective view of one form of my device.

Figure 2 is a side elevation thereof, and illustrates several positions of the seat and carrying means thereof, in full and dotted lines, together with a detachable and combined footrest and food tray attached to the seat, in the full line position thereof.

Figure 3 is a perspective view of the combined footrest and food tray, shown in Figure 2.

Figure 4 is a side elevation of a modified form illustrating modifications of a footrest and a food tray, in use in full lines and out of use in dotted lines.

Figure 5 is a top plan view of the form of Figure 4.

Figure 6 is a perspective view of the food tray shown in Figures 4 and 5.

Figure 7 is a perspective view of the footrest shown in Figures 4 and 5.

Figure 8 is a sectional view taken approximately on line 8—8 of Figure 4, looking in the direction of the arrows.

Figure 9 is a sectional view taken approximately on line 9—9 of Figure 4, looking in the direction of the arrows.

Figure 10 is a perspective view of a modified form of seat that is detachable from the jumper and includes an attachment for applying the seat to a seat of a motor vehicle.

Referring to the drawings in detail, and particularly to the form of Figures 1 and 2, it will be noted that the base frame of that form includes a pair of strip like side members 1 disposed in rearward diverging relation to each other and secured to and bridging the side members substantially midway their ends is a cross brace 2. The rear end portions of the side members 1 are enlarged vertically to reinforce the same, and secured to and rising from the rear ends is an upright 3.

Secured midway its ends to the lower end of the upright and to the rear face thereof is a head strip member 4 that has mounted in the ends thereof, casters 5 and the forward ends of the side members 1 likewise have casters 6 mounted therein to cooperate with the casters 5 to bring about the perambulator function of the device. For that purpose, a handle is also provided for the device and which includes a pair of parallel arms 7 secured to the sides of the upright adjacent to its upper end, for disposal at an upward and rearward inclination therefrom, the arms gradually decreasing in width toward their upper ends and fixed to and extending through the arms in bridging relation thereto, as well as laterally thereof, is a rod like member 8 that provides hand grips 9.

The seat of the form of Figures 1 and 2 includes a bottom 10, side walls 11 and a back rest 12, the latter having a rounded top and secured to the upper edges of the side walls 11 and extending forwardly therefrom is a horizontally disposed substantially U-shaped guard member 13 that may be covered with rubber or the like. The guard member may be formed from a metallic rod having a rubber sleeve thereon. A tongue 14 is formed on or otherwise secured to and extends centrally from the forward end of the bottom 10 and fixed to and extending between the forward portions of the guard member 13 and the tongue 14 is an upright 15 which cooperates with the guard member and the tongue to hold a child on the seat, as will be apparent upon inspection of Figure 1.

The seat is connected to the upright 3 for swinging movement in a vertical plane and for that purpose I provide two pair of leaf hinges

16 and 17 respectively, the hinges 16 each having one of their leaves secured to the front face of the upright 3, while the hinges 17 each have one of their leaves secured to the rear face of the back rest 12, the hinges being disposed in superimposed relation, as best shown in Figure 2. The other leaves of the hinges 16 and 17 have secured thereto the ends of connecting bars 18, and the bars are of a length so that the ends thereof will be spaced from the upright and the back rest to allow free swinging movement of the seat, as indicated in full and dotted lines in Figure 2. Coil springs 19 have one of their ends connected to the back rest adjacent the lower end thereof, and the opposite ends of the springs are connected to the upright adjacent its upper end and the coil springs act to resiliently support the seat and to bring about the jumper function of the device.

When it is desired to use the device as a high chair the seat is held in the upper dotted line position of Figure 2, by a hook and eye, in the form shown, the hook 20 being pivotally connected to the lower bar 18 and the eye 21 is secured to the upper bar to receive the hook, to hold the bars against movement, and consequently the seat in an elevated or high chair position.

The combined footrest and food tray, as best shown in Figure 3, includes side walls or parallel members 22 that are reduced toward their rear ends and the side walls have registering slots 23 therein that open through the rear ends thereof, for the purpose of slidably receiving the bottom 10 therein for securing the rest and tray to the seat. The forward portions of the side walls 22 extend slightly above the remaining portions thereof, as at 24 and secured to and bridging the portions 24 is a tray member 25. Secured to and bridging the side walls 22 adjacent the lower end thereof is a rear wall 26 and a foot strip 27 which are disposed at a rearward angle, as best shown in dotted lines in Figure 2, the wall 26 being adapted to receive the legs of the child, while the strip 27 receives the feet.

It will be obvious that the combined footrest and food tray can be readily applied and removed with respect to the seat, and is held in applied position thereon against casual removal or displacement, in that the slots 23 are of a width to frictionally engage the upper and lower faces of the bottom 10.

The form of Figures 4 and 5 is similar in many respects to the form of Figures 1 and 2, in that it includes a base frame that also is provided with rearwardly diverging side members 28 having enlarged rear portions. However, the latter are fixed to the opposite sides of an upright block 29 which has detachably secured thereto by bolt and wing nut connections 30, the lower end of an upright 31, and the lower connection 30 also secures a head strip 32 to the outer face of the upright, as best shown in Figure 9. A cross brace 33 is secured to and between the side members 28 and casters 34 are mounted in the opposite ends of the strip 32 and the forward ends of the side members 28, to bring about the perambulator function of the device.

The seat of the form of Figures 4 and 5 includes a bottom 35, side walls 36 and a rearwardly inclined back rest 37, the latter having secured thereto one of the leaves of a pair of superimposed hinges 38, and one of the leaves of a pair of superimposed hinges 39 are secured to the upright 31, while the other leaves of the hinges are

secured to the ends of connecting bars 40, so that the seat of this form is likewise mounted for swinging movement relative to the upright. The pins of the hinges of this form, are removable to allow the seat to be removed from the bars if desired, and for a purpose which will be later described. The seat of the form of Figures 1 and 2 may likewise be removable.

A pair of coil springs 41 have one of their ends connected to the lower end of the back rest 37, and the opposite ends of the coil springs are connected to the sides of the upright 31 by screw eyes 42. It will be noted from Figure 4 that the sides of the upright are provided with rows of holes 43, and any pair of holes are adapted to receive screw eyes 42 for adjusting the tension of the springs in accordance with the weight of a child, as will be apparent.

The lower connecting bar has connected thereto a hook 44 to be received in a screw eye 45 on the upper bar, for holding the seat elevated and against swinging action, so that this form can likewise be used as a high chair. Suitable means, such as an open screw eye 46 may be secured to the lower bar to receive and hold the hook against movement, when the latter is not in use.

The seat of the form of Figures 4 and 5 also includes a U-shaped guard member 47 secured to and extending forwardly from the upper ends 30 of the side walls 36 and fixed on and extending centrally and forwardly from the bottom 35 is a leg straddling tongue 48, having an upright 49 secured to and rising from the forward end thereof. The upright of this form has a handle bar 35 50 secured thereto through the medium of a block 51, and the guard member 47 may be covered with rubber or the like.

The propelling handle of the form of Figures 4 and 5 includes a pair of parallel arms 52 secured to the sides of a strip 53 that is formed with a tenon 54 on the forward end thereof, and the upright 31 is mortised to receive the tenon that is secured in place by a wedge 55. The arms 52 have their inner ends bearing against the upright and the arms decrease in width toward their outer ends, the latter having secured thereto a handle bar providing grips 56 having holes 57 extending axially therein from their ends, for a purpose which will be later described.

The tray structure to be used with the form of Figures 4 and 5 is best shown in Figure 6, and includes a tray portion 58 having arms 59 secured to the under face thereof and extending rearwardly therefrom, the arms having headed spring pressed pins 60 mounted in bores extending transversely therethrough adjacent their rear ends, as best shown in Figure 8, which likewise illustrates that the shanks of the pins normally extend through the inner faces of the arms 59 to be received in holes 61 in the sides of the back rest 37 to pivotally and detachably secure the tray structure to the back rest, for the arms to normally rest on the guard member 47, when the tray is in place for use, as best shown in Figure 4.

The footrest as shown in Figure 7, can be used on the seat of either form, and includes a pair of side members of angle formation to provide horizontal upper rear portions 62 and forwardly and downwardly inclined front portions 63, the latter having secured to and bridging the lower ends thereof, a rearwardly and downwardly inclined foot receiving strip 64. The portions 62 have registering slots 65 extending along the longitudinal center thereof and the slots open

through the rear ends of the portions 62 for applying the footrest to the bottom 35 of the seat, it being understood that the slots are of a width to frictionally fit the bottom 35 to detachably secure the footrest to the seat, as will be apparent.

When the tray structure and footrest of the form of Figures 4 and 5 is not in use, the footrest may be applied to the tray portion 58, as shown in dotted lines in Figure 4, and the tray structure to the hand grips 56, by inserting the pins 60 of the arms 59, in the holes 57 of the grips 56, with the result it will be seen that the tray structure and footrest can be carried by the propelling handle.

The seat of either form may be removable from the supporting bars thereof, as previously indicated, and in Figure 10 I have illustrated the seat of the form of Figures 4 and 5 removed from the bars, and with a bracket detachably secured to the back rest 37 for applying the seat to the back of a seat of a motor vehicle or the like. The bracket which is preferably formed from a single strand of wire is substantially in the form of a bail and includes an arcuate or hook shaped upper portion 65 for disposal about the top of the vehicle seat and one arm 67 of the bracket is longer than the other arm 68. The lower ends of the arms 67 and 68 are bent inwardly at right angles to the remaining portions thereof to provide attaching fingers 69 and 70 respectively, and the finger 69 is inserted in the barrel of the leaf of the upper hinge 38, while the finger 70 is inserted in the barrel of the leaf of the lower hinge 38. In order to hold the fingers in the barrels against casual removal, I provide an elongated looped member 71 slidably mounted on and bridging the arms 67 and 68 and a fastening member 72 which may be an open screw eye is secured to the back rest 37 to hold the arm 67 against the same, as shown.

By removing the seat from the jumper structure and attaching the bracket thereto in the manner set forth, it will be obvious that the jumper seat can be applied to the seat of the vehicle for use by a child when riding therein.

From the above description and disclosure in the drawings, it will be further obvious that either form of my device can be used either as a jumper, high chair or perambulator, and the form of Figures 4 and 5 can also be used as a walker by adjusting the springs 41 so that the weight of the child causes the seat of that form to be lowered to a position for the child's feet to engage the ground, it being apparent that the footrest is removed when the device is used as a walker.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A baby jumper comprising a base including a pair of rearwardly diverging side members, an upright secured to the rear ends of the side members, a head strip included in the base and secured midway its ends to the lower end of the upright, caster wheels mounted in the forward ends of the side members and the ends of the head strip, a pair of superimposed bars having one of their ends hinged to the upright, a seat including a back rest hinged to the opposite ends of the bars for the seat to overlie the base for

swinging movement, a bottom and side walls included in said seat, a leg straddling tongue formed on the bottom and extending centrally and forwardly therefrom, a guard member secured to

5 the side walls and extending forwardly therefrom, an upright between the tongue and the guard member, and coil springs having their ends connected to the first mentioned upright and said back rest respectively for resiliently supporting the seat.

2. A baby jumper comprising a base, an upright secured to and rising from the base, a pair of superimposed bars having one of their ends hinged to the upright, a seat hinged to the oppo-

15 site ends of the bars to overlie the base for swinging movement, coil springs having their ends connected to the upright and seat respectively for resiliently supporting the seat, a hook secured to one of said bars adjacent one end, and a screw eye secured to the other bar a greater distance from the end of the bar than the eye to receive said hook for holding said seat elevated and against swinging movement.

3. A baby jumper comprising a base, an upright secured to and rising from the base, a pair of superimposed bars having one of their ends hinged to the upright, a seat hinged to the oppo-

20 site ends of the bars to overlie the base for swinging movement, said seat including a back rest, a bottom and side walls, coil springs having their ends connected to the upright and the back rest respectively for resiliently supporting the seat, and a footrest including side members slotted to frictionally receive the bottom of the seat therein for detachably securing the footrest to the seat.

4. A baby jumper comprising a base, an upright secured to and rising from the base, a pair of superimposed bars having one of their ends hinged to the upright, a seat hinged to the opposite ends of the bars to overlie the base for swinging move-

30 ment, said seat including a back rest, a bottom and side walls, coil springs having their ends connected to the upright and the back rest respectively for resiliently supporting the seat, a footrest including side members slotted to frictionally receive the bottom of the seat therein for detachably securing the footrest to the seat, and a food tray secured to and bridging the upper ends of the side members.

5. A baby jumper comprising a base, an upright secured to and rising from the base, a pair of superimposed bars having one of their ends secured to the upright, a seat hinged to the oppo-

35 site ends of the bars to overlie the base for swinging movement, said seat including a back rest, a bottom and side walls, coil springs having their ends connected to the upright and back rest respectively for resiliently supporting the seat, a footrest including side members providing horizontal upper end portions slotted to frictionally receive the bottom of the seat therein for detachably securing the footrest to the seat, forwardly and downwardly inclined front portions

40 formed on the rear portions, and a rearwardly and downwardly inclined foot receiving strip secured to and bridging the lower ends of the front portions.

6. A removable seat for a baby jumper, hinges for connecting the seat to jumper structure and including barrel type leaves detachable from each other, certain of the leaves being secured to the seat, and a substantially bail shaped bracket comprising a pair of spaced parallel arms having their eight end portions curved in hooked for-

mation, fingers formed on the opposite ends of the arms and to be mounted in the barrels of the leaves secured to the seat, means slidably mounted on the arms for holding said fingers in said barrels, means secured to the seat and co-operating with the fingers and barrels for detachably securing the brackets to the seat, and the hooked end portions of the arms being adapted for disposal about the top of a vehicle seat for mounting the jumper seat thereon.

7. A baby jumper comprising a base, an upright secured to and rising from the base, a pair

of superimposed bars having one of their ends hinged to the upright, a seat hinged to the opposite ends of the bars to overlie the base for swinging movement, said seat including a back, a bottom and side walls, coil springs having their ends connected to the upright and the back respectively for resiliently supporting the seat, and a foot rest including side members slotted to frictionally receive the bottom of the seat therein

5 for detachably securing the foot rest to the seat.

HOWARD W. ANDERSON.
